UNITED STATES PATENT OFFICE.

WILLIAM T. KING, OF TALLAPOOSA, GEORGIA.

WASHING-MACHINE.

SPECIFICATION forming part of Letters Patent No. 609,550, dated August 23, 1898.

Application filed July 8, 1897. Serial No. 643,870. (Model.)

To all whom it may concern:

Be it known that I, WILLIAM T. KING, a citizen of the United States, residing at Tallapoosa, in the county of Haralson and State of Georgia, have invented a new and useful 5 Washing-Machine, of which the following is a specification.

This invention relates to washing-machines which operate by the combined action of a pounder and the forced circulation of steam and suds-water through the clothing or articles undergoing treatment in opposite directions.

The invention consists of the novel instrumentalities for attaining the end in view; and for a full understanding of the merits and advantages of the invention reference is to be had to the accompanying drawings and the following description.

o The improvement is susceptible of various changes in the form, proportion, and the minor details of construction without departing from the principle or sacrificing any of the advantages thereof, and to a full disclosure of 5 the invention an adaptation thereof is shown in the accompanying drawings, in which—

Figure 1 is a perspective view of a washing-machine of special design for attaining the objects of this invention. Fig. 2 is a vertical central section thereof. Fig. 3 is a perspective view of the inner vessel detached from the boiler and inverted. Fig. 4 is a perspective view of the combined plunger and pounder as it appears when inverted.

Corresponding and like parts are referred to in the following description and indicated in the several views of the drawings by the same reference characters.

The boiler 1 for containing the suds-water may be of suitable size and shape and, as shown, is of cylindrical form and is closed at its upper end by a conical cover 2, held in place by fastenings 3 and centrally apertured for the passage of the stem 4, bearing the combined plunger and pounder 5. A bracket 6 is secured to a side of the boiler at its upper end, and a link 7 has pivotal connection at its lower end with the bracket, and its upper end receives the short arm of a lever 8, which is pivoted thereto and to the upper end of the

stem 4, and by means of which the plunger is reciprocated in the boiler.

A vessel 9 is removably fitted within the boiler and is provided at its lower side with supports 10, which rest upon the bottom of the boiler and hold the vessel a short distance therefrom, so as to leave a space between the opposing sides of the bottoms. The inner vessel is smaller than the boiler, so as to provide a space 11 between the opposing sides, 55 which is closed at its upper end by an outer flange 12 of the inner vessel, said flange being formed by turning the upper end portion of the sides of the vessel outward, as indicated. A series of perforations 13 are formed in the 60 sides of the vessel a short distance from the outer flange 12 and establish communication between the space 11 and the interior of the vessel and upper portion of the boiler for the escape of steam and egress and ingress of the 65 suds-water. The bottom of the vessel is centrally perforated, and a plate 14 spans the perforations and is soldered or otherwise secured at its terminals to the bottom of the vessel, upon opposite sides of the perforations, and 70 forms a guard to prevent the clothing crowding upon the openings and serves as a handle to admit of the vessel being removed when desired. A valve 15 closes upwardly against the bottom of the vessel 9 and is held in place in 75 notches formed in the upper edges of the supports 10, the latter being metallic strips bent into an approximately V form and secured to the bottom of the vessel in radial disposition, substantially as illustrated.

The plunger comprises a conical-shaped plate 16, having a depending flange, and is secured centrally to the stem 4 a short distance from its lower end. Beaters or pounders 17, consisting of strips or bars, connect 80 the lower end of the stem 4 with the edge portion of the plate 16 and comprise vertical members 18 and horizontal members 19, the latter being fluted, crimped, or corrugated, so as to press upon the clothing or articles in such a manner as to secure a positive movement of the suds-water therethrough by a squeezing or compressing action. These beaters mutually coöperate to stiffen and strengthen the 85 lower end of the stem 4 and the outer edge 90 100

of the plate 16 and are adapted to enter the upper portion of the vessel 9, the plate being of a size to engage with the outer flange 12 and be limited in its downward movement 5 thereby. A valve 20 closes upwardly against the lower end of the stem 4 and is retained in place by a cage 21, consisting of crossing wires secured at their bent ends to the inner ends of the horizontal members 19. The stem 10 4, which is tubular, is closed at its upper end, and a series of openings 22 are formed in its sides above the conical plate 16 for the passage of air and steam.

The clothing or other articles to be washed 15 are placed in the vessel 9, and the boiler is supplied with a suitable quantity of suds-water, after which the plunger, with the cover, is placed in position, when the machine is in condition for operation, the cover being secured 20 against accidental displacement by the fasteners 3. When heat is supplied to the boiler 1 and the water begins to boil, steam will pass through the openings at the valve 15, and as the boiling continues the steam 25 will accumulate and seat the valve, thereby causing steam and the water to pass up into the space 11 and through the openings 13. In a short time the upward pressure within the receptacle 9 and above the valve will exceed 30 the pressure upon the lower face of the latter, and the valve will open and permit the suds-water to flow from the vessel 9 into the space 11. When this water again boils, the valve will be closed and the above-described 35 circulation of water will be repeated, the action of the valve being automatic.

The plunger fits snugly within the boiler, and the lower fluted portions strike the clothes and operate similar to a clothes-pounder and 40 assist the operation of washing. The valve

20 closes on the downstroke and opens on the upstroke to relieve the pressure and thereby facilitate the lifting of the plunger.

Having thus described the invention, what is claimed as new is—

1. In a washing-machine, the combination of a boiler, a plunger operating in the upper portion of the boiler, a vessel centrally apertured and of less diameter than the boiler and located in the lower portion thereof providing an annular space and having its upper edge bent outwardly to close the said space, radial strips secured to the bottom of the vessel and forming supports therefor and having their inner upper edges notched, a valve operating in the space formed by notching the supporting-strips and closing against the bottom of the vessel, and a plate spanning the valve-controlled perforate portion of the bottom of the said vessel and secured at its extremities thereto and serving as a guard and handle, substantially as set forth.

2. In a washing-machine, the combination of a boiler, a vessel located within the lower portion of the boiler and having a space between its bottom and sides and the corresponding parts of the boiler, and provided in its bottom with a valve-controlled opening, a plunger operating in the upper portion of the boiler and comprising a hollow stem having openings in its sides above the plunger-head, and a valve for closing the lower end of the stem, substantially as and for the purpose set forth.

In testimony that I claim the foregoing as my own I have hereto affixed my signature in the presence of two witnesses.

WILLIAM T. KING.
